UNITED STATES PATENT OFFICE.

HENRY W. SUMNER, OF SEATTLE, WASHINGTON.

ADVERTISING DEVICE.

Application filed March 19, 1921, Serial No. 453,648. Renewed March 1, 1923.

To all whom it may concern:

Be it known that I, HENRY W. SUMNER, a citizen of the United States, residing at Seattle, in the county of King and State of

5 Washington, have invented a certain new and useful Improvement in Advertising Devices, of which the following is a specification.

This invention relates to improvements in 10 machines for displaying advertising matter and the object of this improvement is to provide an automatic machine that is arranged to receive a plurality of curtains on which advertising matter is inscribed and to 15 display the said curtains successively.

Another object is to construct a machine 20 of this nature comprising a rectangular frame having means at each end for receiving and holding a plurality of curtain 25 rollers and having automatic mechanism for successively engaging with or picking up the said rollers at the ends of the frame at which they are normally held and carrying the same to the opposite end of the 30 frame, to thereby unwind the curtains from the rollers and display the advertising matter thereon, the outer end of each curtain being secured to the frame and each curtain being provided with a spring that always 35 tends to keep the curtain wound upon the roller.

A further object is to provide an advertising device of this nature having a transversely arranged traveller bar that engages 40 with and moves the curtain rollers, the said traveller bar being driven by an endless cable that is connected with the two opposite ends of the traveller bar and moves the said two ends in the same direction and at 45 the same rate of speed at all times.

A further object is to provide novel and efficient automatic control and timing mechanism that is capable of a wide range of adjustments and that renders the machine 50 suitable for use in combination with apparatus for producing different lighting effects on the curtains.

A further object is to provide a machine 55 of this nature in which curtains of any thickness or material may be used and one in which the curtains are always under tension exerted by a spring within the roller when they are being exhibited thus automatically taking care of any expansion or 60 contraction of the curtains and preventing them from becoming loose and baggy.

A still further object is to provide a simple and efficient slow speed power transmission that will run for long periods of time without attention.

With the above and other objects in view, 60 the invention consists in the novel construction, adaptation and combination of parts as will be more clearly hereinafter described and claimed.

In the accompanying drawings Figure 1 65 is a view in front elevation of a device constructed in accordance with this invention showing the curtain rollers in their proper places but omitting the curtains.

Fig. 2 is a view in side elevation showing 70 one side of the same.

Fig. 3 is a view in side elevation showing the opposite side of the same.

Fig. 4 is an enlarged fragmentary view in 75 cross section on broken line 4, 4 of Fig. 1 showing the rollers with the curtains mounted thereon and showing certain parts broken away to better reveal the construction of certain other parts.

Fig. 5 is a view in elevation of one end of 80 a traveler bar by which the rollers are picked up and carried from one end to the other of the frame.

Fig. 6 is a view showing the development 85 of a cam embodied in the machine.

Fig. 7 is a fragmentary view partly in section and partly in elevation of a spring roller.

Fig. 8 is an enlarged sectional view 90 through the cable drum and driving mechanism therefor.

Fig. 9 is a view in elevation showing parts 95 of the driving mechanism as they might appear if removed from their housing.

Fig. 10 is a detail partly in elevation and partly in section showing parts of the locking mechanism for the cable drum.

Fig. 11 is a fragmentary view in elevation 100 showing certain lugs on the cable drum between which a locking pawl is arranged to enter.

Referring to the drawings, I have shown two normally upright side members 10 and 11 that are rigidly supported in spaced 105 apart relation by end supports 12 and 13 in such a manner as to form a rectangular frame.

The side members 10 and 11 are preferably of cast metal and are provided near 110 their two ends with oppositely disposed bearings for the reception of transverse

shafts 14 and 15 upon which are secured disks or plates 16 one of such disks or plates being located adjacent to each end of each of the shafts and just inside of the side members.

Each of the disks 16 is provided at a plurality of equidistantly spaced points with peripheral notches 17 for the reception of the outwardly projecting end members 18 and 18' of two part rollers that are made up of tubular inner rollers 21 to the inner ends of which display curtains 22 may be secured, and tubular outer rollers 29 about which the curtains 22 are wound the said curtains passing outwardly through slots 29' in the tubular outer rollers and the outer ends of such curtains being secured to equidistantly spaced transverse rods 23 that extend crosswise between the two disks 16 on each of the shafts 14 and 15.

The rollers 21 are internally provided with springs 20 that are connected with rods 24 that project outwardly through the end members 18 and 18' and have ratchet connections with such end members as more clearly shown in Fig. 7 whereby the springs are maintained under tension, the members 18 being square in cross section to prevent them from turning in the notches 17.

The side members 10 and 11 are each provided adjacent each end and below the bearings of the shafts 14 and 15 with substantially semicircular guide flanges 25 that are located near the disks 16 and that serve as guides to assist in preventing the end members 18 and 18' of the rollers 21 from dropping out of the notches 17. The tension under which the curtains are maintained by their respective springs also tends to hold the end members 18 and 18' within the notches 17.

The side members 10 and 11 are each further provided with longitudinally extending guide slots 26 at the edges of which are formed inwardly projecting flanges 27. The guide slots 26 are arranged to slidably receive the ends 28 of a vertically movable traveller bar 30 that extends crosswise of the display frame and is provided on the exterior of each of the side frame pieces 10 and 11 with pins 31 that prevent endwise movement of such bar.

The end portions 28 of the traveller bar 30 that fit between the guide flanges 27 are notched as at 32 for the reception of the outwardly projecting ends 18 and 18' of the curtain rods 20, while the extreme outer ends of such bar project a short distance beyond the outer surfaces of the side members 10 and 11 and are bifurcated as at 33 for the reception of an endless cable 34. The bar 30 is adapted to have a plate 30' secured thereto as shown in Figs. 1 and 4.

The cable 34 is wound several turns around a drum 35 so that when the drum is

rotated the cable will wind upon the drum at the same rate of speed at which it unwinds and will be driven over the several pulleys over which it passes without change of length.

The path of the cable 34 may be traced as follows: starting from the drum 35, thence downwardly around a pulley 36, thence upwardly through the bifurcated end 33 of the bar 30 to which the cable is rigidly secured, thence successively over two pulleys 37 and 38, across the display frame and around a pulley 40, on the frame member 11, thence downwardly around a pulley 41, thence upwardly through the bifurcated end 33 of the cross bar 30; thence over two other pulleys 42 and 43, thence across the display frame and over a pulley 44 and thence downwardly to the drum 35, the arrangement being such that when the cable is moved the two portions to which the opposite ends of the bar 30 are secured will always move in the same direction and at the same rate of speed thereby moving the bar 30 lengthwise of the frame and at the same time always keeping such bar at right angles to the side members 10 and 11 so that it will move smoothly and evenly and will not catch or bind.

The drum 35 is mounted for rotation on a bearing stud 45, see Fig. 8, and is rigidly connected with a bevel gear 46 that meshes with two other bevel gears 47 and 48 having integrally formed sleeves 50 that are journaled in a bearing bracket 51 and that have a driven shaft 52 extending axially therethrough, the driven shaft being free to rotate within the sleeves 50 without turning the bevel gears.

The bottom end of the shaft 52 is connected by bevel gears 53 with a short transverse shaft 54 having a worm wheel 55 that meshes with a worm 56 on the shaft 57' of a motor 57.

The sleeves 50 are each provided on their outer end with a flange 58 to which is secured a clutch plate 59 having a lug 60 that projects outwardly therefrom. The lugs 60 are adapted to be engaged by other lugs 61 on the end of the shifter collars 62 that are integral with sleeves 63 that are movable lengthwise of the shaft 52 and are connected with such shaft by pins 64 that project outwardly through slots 65 in the sleeves.

The sleeves 63 are moved by shifter arms 66 that engage at one end with the shifter collars 62 and are medially fulcrumed on brackets 68 that project outwardly from the bearings 51. The outer ends of the shifter arms 66 are provided with rollers 69 that engage within cam slots 70 in cam members 71 that are mounted on a vertical shaft 72.

The shaft 72 is driven by means of a worm 73 that meshes with another worm 74 on the motor driven shaft 54.

The outer ends of the sleeves 63 are provided with flanges 75 having lugs 76 that are arranged to engage with other lugs 77 on the ends of worms 78 that mesh with worm 5 wheels 79 on the ends of the transverse shafts 14 and 15.

The shafts 14 and 15 are provided on the ends opposite the worm wheels 79 with star wheels 80 of a form more clearly shown in 10 Fig. 3 that are yieldingly engaged by pins 81 on the ends of arms 82 that are secured by pivots 83 to the frame member 11 and are held in engagement with the star wheels by compression springs 84.

15 The pulley 41, Figs. 1 and 3, over which the cable 34 passes is journaled in a bracket 85 having a shank 86 that is slidable in a rigid support 87 on the frame and that has a compression spring 88 interposed between 20 the bracket 85 and support 87 to keep the cable 34 taut at all times and to permit the cable to yield slightly in case the clutch through which the cable drum is driven is not disconnected at the exact instant that 25 the traveller bar reaches the limit of its upward or downward movement.

When the drum is not being rotated it is locked in a fixed position by a locking lever 90 that is fixedly mounted on a vertical shaft 30 91 and is adapted to protrude between two lugs 92 on the rear side of the drum 35. The lever 90 is urged into engagement with the drum 35 by a torsion spring 93 on the shaft 91 and is moved away from the drum 35 into the position shown in Fig. 10 by a double cam 94 that is mounted on the shaft 72 and is arranged to engage with a cam lever 95 on the shaft 91. The shaft 91 is journaled in brackets 96 that also form 40 bearings for the shaft 72.

The shaft 72 necessarily rotates at a comparatively slow rate of speed while the traveller bar 30 makes one complete excursion and the drum 35 is locked and unlocked 45 twice during each complete revolution of such shaft.

When the magazines are not in motion one of the notches 17 in each of the disks 16 will always be in line with the slots 26 in 50 the upright frame members and as the traveller bar carrying the curtain rollers approaches the limit of its upward or downward movement the ends 18 and 18' of the rollers will enter the notches 17 and at the 55 next forward movement of the magazine the roller that has been held within the traveller bar will be removed therefrom and replaced by the next adjacent roller in the magazine.

60 As the traveler bar 30 moves between the two ends of the frame the curtain from one of the rollers that is held therein will always be unrolling while the curtain from the other roller will always be rolling up but 65 the rollers will be hidden by the bar 30 to

such an extent that it will be difficult for an observer to see where the curtain that is being rolled up goes to, or where the unrolling curtain comes from thus lending an air of mystery to the device that arouses interest and causes persons to give attention to the advertising matter on the curtains. 70

The fact that the curtains themselves do not move and that all advertising matter that is exposed to view remains stationary 75 makes the device more mysterious and attractive and makes it easier to read the printed matter than it would be if the curtains themselves moved.

The entire machine is preferably enclosed 80 within an ornamental housing not shown that is provided with a suitable sight opening through which the curtains may be viewed.

The machine herein disclosed is adapted 85 for the reception of twenty curtains, ten at each end, but it will be understood that these machines may be designed to receive and display either more or less than that 90 number of curtains.

In operation the several parts of the machine are properly adjusted and timed and the rollers with the curtains wound thereon and the ends of such curtains secured to the rods 23 are placed in the machine, preferably with two of the rollers in the notches 32 in the ends of the bar 30. 95

The shape of the cam slots 70 determines the movements of the traveller bar 30 and the periods of rest of such bar at the top and bottom of the frame and also determines the movements of the shafts 14 and 15 which together with the disks 16 constitute the magazines that carry the rollers and it is obvious that many variations in the shape 100 of these cam slots may be made to secure the proper sequence and timing of the various movements.

In the drawings I have shown duplicate cams which are designed to secure a sequence of movements that has been found very satisfactory in the operation of machines of this nature. Referring to Fig. 6 if we assume that the traveller bar 30 is at the lowermost limit of its movement and the roller 69 on the lower lever arm 66 has been traveling in the straight portion *b* of the cam slot and has just reached the inclined portion *a* in such cam slot then the sequence of operations will be as follows. The movement imparted to the lever arm 66 by the inclined portion *a* of the cam slot will move the lower clutch element 76 into engagement with the clutch element 77 on the worm 78 and while the roller 69 is travelling in the cam section *b* the worm 78 will turn the shaft 15 far enough to remove one roller from the notches 32 in the traveler bar and bring the next roller into registration with such notches. The movement imparted by 110 115 120 125 130

the cam section *c* will disconnect the clutch elements 76 and 77 and the clutches at both ends of the lower sleeve 63 will remain disconnected while the roller 69 is in the cam section *d*. The movement imparted by the cam section *e* will connect the clutch member 61 at the upper end of the sleeve 63 with the clutch member 60 thereby rotating the gear 47 which will in turn, rotate the drum 10 35 and cause the traveler bar 30 to be moved from its lowermost to its uppermost position while the roller 69 is in the straight section *f* of the cam slot. As the traveler bar approaches the uppermost position the 15 roller 69 will pass into the inclined section *g* of the slot and the clutch member 61 will be disconnected from the clutch member 60 just as the traveler bar reaches the limit of its upward movement, the roller 69 then 20 passing into the straight slot section *h* in which position the clutches at both ends of the sleeve 63 will be disengaged.

During the sequence of operations just above described the roller 69 of the uppermost cam lever has been traveling in the straight slot *h* of its cam and the clutches on the uppermost sleeve 63 have been in a neutral position but during the time that the roller 69 on the lowermost cam lever is 30 traveling in the straight section *h* of its cam slot the roller 69 on the uppermost cam lever will pass successively through the cam slot sections *a*, *b*, *c*, *d*, *e*, *f* and *g* of its cam thus successively causing the uppermost 35 clutches 75 and 76 to be engaged, the upper magazine to be advanced from one position to the next succeeding position, the uppermost clutches 75 and 76 to be disengaged, the clutch 61 on the uppermost sleeve to be 40 engaged with the clutch 60 on the sleeve of the gearwheel 48 the drum 35 to be rotated to move the traveler bar downwardly to its lowermost position and the uppermost clutch members 61 and 60 to be disengaged. 45 The positions of the upper and lower cam members 71 are necessarily reversed with respect to each other.

From the above description it is apparent that while the various parts that are controlled by one cam are performing a series of operations the parts that are controlled by the other cam are in a neutral position and vice versa and it is also apparent that by varying the shape and dimensions of 55 the various portions of the cam slot the sequence and timing of the several operations may be varied.

The shaft 72 which is the shaft that controls the movements of the various parts 60 is driven at a very slow rate of speed while the shaft 52 which is the shaft that transmits the power necessary to perform the various movements is also driven at a relatively slow rate of speed but rotates considerably faster than the shaft 72.

From the foregoing description taken in connection with the accompanying drawings the form of construction and method of operation of this advertising device will be readily apparent, but, while I have described the principle of operation of the invention together with the device which I now consider to be the best embodiment thereof it will be understood that the device shown is merely illustrative and that such changes may be made as are within the scope of the following claims.

I claim—

1. A device of the class described comprising an upright frame, a roller receiving magazine at each end of said frame, spring rollers arranged to be removably held by said magazines, a display curtain arranged to wind on each of said spring rollers, one end of each display curtain being secured to its roller and the other end being secured to the magazine, a traveler bar disposed transversely of said frame and movable lengthwise thereof and arranged to successively pick up the rollers and display the curtains 90 by moving the rollers away from the magazines and then returning the said rollers to the magazines, and an endless driven cable connected with both ends of said traveler bar for moving the same. 95

2. A device of the class described comprising an upright frame, a roller receiving magazine at each end of said frame, spring rollers arranged to be removably held by said magazines, a display curtain arranged 100 to wind on each of said spring rollers, one end of each display curtain being secured to its roller and the other end being secured to the magazine, roller carrying means movable between said two magazines for automatically engaging said rollers to withdraw them from and return them to the said magazines, an endless cable connected with said roller carrying devices at both sides of said frame, means on one side of said frame 110 for driving said cable, automatic timing devices for said cable driving means and means connected with said automatic timing devices for intermittently moving said magazines. 115

3. A device of the class described comprising an upright frame, a roller receiving magazine at each end of said frame, spring rollers arranged to be removably held by said magazines, a display curtain arranged 120 to wind on each of said spring rollers, one end of each display curtain being secured to its roller and the other end being secured to the magazine, a traveler bar for engaging with the rollers and removing them from the magazines, an endless cable connected with the ends of said traveler bar for moving the same, means for driving said cable, means for advancing said magazines, and automatic timing devices controlling the 125 130

movements of said traveler bar and said magazines.

4. A device of the class described comprising a frame having two upright side members that are provided with longitudinally arranged slots, a roller receiving magazine disposed at each end of said frame said magazines each including two disks disposed near the respective side members and having peripheral notches that register with said slots, spring rollers having bearing members arranged to fit within the notches in said disks, a traveler bar extending crosswise of said frame and guided for movement within said slots, said traveler bar having notches in the ends thereof that are arranged to register with the notches in said disks and to receive the bearing members on the ends of said rollers, means for moving said traveler bar, and means for advancing said magazines.

5. A device of the class described comprising a frame having two upright side members that are provided with longitudinally arranged slots, a shaft disposed near the end of said slots, disks secured to said shaft near each of said side members, said disks having radially arranged peripheral notches that register with the slots in said side members, rollers having bearing members arranged to fit in said notches and means movable in said slots for engaging with said bearing members and removing said rollers from said disks.

35 6. A device of the class described comprising an upright frame, a roller receiving magazine at each end of said frame, spring rollers arranged to be removably held by said magazines, a display curtain arranged to wind on each of said spring rollers said curtains each having one end secured to its roller and the other end secured to its magazine, roller transporting means arranged to engage with the rollers in said magazines and withdraw the same from the magazines to display said curtains, a driving member at one side of the frame for advancing said magazines, an endless cable propelled by said driving member for moving said roller transporting means and a timing member connected with said driving member for controlling the movements of said roller transporting means and said magazines.

7. A device of the class described comprising a frame, a roller receiving magazine at each end of said frame, roller transporting devices movable between said magazines, a power shaft arranged at one side of said frame, releasable transmission means connecting said power shaft and said magazines, other releasable transmission means connecting said power shaft and said roller transporting devices, a timing shaft adjacent said power shaft and cam operated means connected with said timing shaft for controlling

the releasable transmission means between said magazines and said power shaft and between said roller transporting means and said power shaft.

8. A device of the class described comprising an upright rectangular frame, a roller receiving magazine rotatably mounted adjacent each end of said frame, a driven power shaft arranged at one side of said frame, worm gear transmissions connecting said shaft and said magazines, clutches interposed between said shaft and said worm gears, a traveler bar movable vertically of said frame, a cable connected with opposite ends of said traveler bar for moving the same, sheaves for said cable said sheaves being arranged so that the two portions of said cable that are secured to said traveler bar will always move in the same direction and at the same rate of speed, a drum whereon said cable is wound, reversible gear mechanism connected with said drum, clutches interposed between said reversible gear mechanism and said driven power shaft, a driven timing shaft, cams on said timing shaft and means governed by said cams for actuating said clutches to advance said magazines and move said traveler bar.

9. A device of the class described comprising a rectangular frame having upright side members provided with longitudinally extending slots, a traveler bar extending crosswise of said frame and guided for movement within said slots, a winding drum, means for driving said winding drum, a cable wound about said drum and arranged to be driven by the turning of said drum, the length of said cable remaining constant, and sheaves for said cable said sheaves being arranged so that said cable extends lengthwise along each side of said frame parallel with said slots, the said cable being secured to the ends of said traveler bar and being arranged to move in the same direction and at the same rate of speed on both sides of said frame.

10. A device of the class described comprising a rectangular frame having upright side members, roller carrying means guided for movement lengthwise of said side members, a winding drum, reversible gear mechanism for rotating said drum, a plurality of sheaves journaled on said frame, an endless cable belt passing over said sheaves and around said drum and arranged to be driven by rotation of said drum the said cable extending along both sides of said frame and being secured on both sides to said roller carrying means and being arranged to move in the same direction and at the same rate of speed on both sides and resilient spring devices connected with one of said sheaves to permit the same to respond to the tension of said cable belt.

11. A device of the class described com-

prising a rectangular frame having upright side members provided with longitudinal slots, a traveler bar movable in said slots, a roller receiving magazine rotatably mounted adjacent each end of said frame and arranged to deliver rollers to said traveler bar and receive rollers from said traveler bar, a power shaft, transmission means interposed between said power shaft and said magazines, said transmission means including clutches, a timing shaft, means connected with said timing shaft for controlling said clutches, sheaves mounted for rotation on

said frame, a cable belt arranged to pass over said sheaves and secured to the two ends of said traveler bar, a drum for driving said cable belt, reversible means connected with said power shaft for rotating said drum, devices connected with said timing shaft for governing said reversible drum rotating means, means for locking said drum and devices connected with said timing shaft for governing said locking devices. 15 20

Seattle, Washington, January 18th, 1921.

HENRY W. SUMNER.
